APPARATUS FOR THE CONTROL OF HIGHWAY CROSSING SIGNALS

Application filed June 4, 1930. Serial No. 459,155.

Our invention relates to apparatus for the control of highway crossing signals, and has for an object the provision of novel and improved controlling apparatus eliminating the necessity for insulated joints in the track rails.

We will describe one form of apparatus embodying our invention, and will then point out the novel features thereof in claims.

10 The accompanying drawing is a diagrammatic view showing one form of apparatus embodying our invention.

Referring to the drawing, the reference characters 1 and 1^a designate the track rails 15 of a railway track A along which traffic normally moves in the direction indicated by the arrow, which track is intersected by a highway H. Located at this intersection is a highway crossing signal S, which, in the form 20 here shown, is an electric bell.

Located between the track rails 1 and 1^a to the right of the highway H, is a transformer G^E, and also located between the rails at the highway H is a second transformer G^F. 25 Each of these transformers comprises a magnetizable core made up of two U-shaped members 20 and 21, which members carry a primary winding 22 and a secondary winding 23, respectively. Each primary winding 22 is 30 constantly supplied with alternating current from a suitable source, which is not shown in the drawing, but the terminals of which are designated X and Y. The secondary 23 of transformer G^E is directly connected with the

35 winding of a relay E, and the secondary of transformer G^F is directly connected with the winding of a relay F. The parts of each transformer are so proportioned that in the absence of a car or train the voltage which is 40 induced in the secondary winding 23 is sufficient to energize the associated relay, but that when the track immediately adjacent the transformer is occupied by a car or train, the wheels and axles and the trucks shunt

45 some of the primary flux from the secondary, so that the voltage induced in the secondary winding is reduced to an amount sufficient to release the associated relay. One form of transformer which may be used in systems 50 embodying our invention, is disclosed and

claimed in application for Letters Patent of the United States filed by P. N. Bossart on April 9, 1930, Serial No. 442,991.

The signal S is controlled by the relays E and F, and also by a signal relay K, a stick 55 relay L, and a slow-acting device M which, as here shown, is a thermostat having a normally open contact 13 and a heating winding 9.

The signal relay K is provided with a 60 pick-up circuit which passes from terminal X, through front contact 11 of relay F, front contact 12 of relay L, contact 13 of thermostat M, and the winding of relay K to terminal Y. It follows that this circuit can 65 be closed when and only when the relays F and L are both closed and the thermostat contact 13 is also closed. Relay K is provided with a stick circuit which passes from terminal X, through front contact 2 of relay 70 E, front contact 3 of relay K, and the winding of relay K to terminal Y.

Relay L is provided with a pick-up circuit which passes from terminal B of a source 75 of direct current, through the back point of contact 5 of relay F, back contact 6 of relay K, and the winding of relay L to terminal C of the same source. This circuit can be closed when and only when both relays F and K are open. Relay L is provided with a stick circuit which passes from terminal B, through front contact 7 of relay L, back contact 6 of relay K, and the winding of relay L to terminal C.

The thermostat winding 9 is provided with 85 a circuit which passes from terminal B, through the front point of contact 5 of relay F, front contact 8 of relay L, winding 9 and back contact 10 of relay K to terminal C.

The crossing bell S is provided with a 90 circuit which passes from terminal B, through back contact 4 of relay K, and the operating magnet of the bell S to terminal C. It follows that the bell will operate when relay K is open.

95 The operation of the apparatus is as follows: Normally relay K is closed by virtue of its stick circuit, so that bell S is silent. When a train moving toward the left passes over transformer G^E, it will momentarily 100

open relay E, thereby opening at contact 2 the stick circuit for relay K, with the result that after relay E closes, relay K will remain open. The circuit for bell S will then be completed at contact 4 of relay K, so that 5 the bell will operate to indicate the approach of the train. When the train passes over transformer G^E, relay F will open, thereby closing the pick-up circuit for relay L through back contacts 5 and 6 of relays F and K, so that relay L will become energized. 10 This relay will then remain energized by virtue of its stick circuit through contacts 7 and 6. When the entire train has passed transformer G^F, relay F will again close and 15 will remain closed, thereby closing the circuit for winding 9 of the thermostat M through contacts 5, 8 and 10. After the expiration of a given interval of time, contact 13 of thermostat M will close, thereby completing the 20 pick-up circuit for relay K through contacts 11, 12 and 13. The closing of relay K will stop the operation of the bell S, and relay K will remain closed because of its stick circuit through contacts 2 and 3. Relay L will 25 then open because its circuits will be open at contact 6, and the thermostat winding 9 will become deenergized because its circuit will be open at contacts 10 and 8.

30 It will be seen from the foregoing that the crossing signal will start to operate when a train passes transformer G^E, but that the signal will not stop operating until a given length of time after the train has passed the transformer G^F. This length of time may 35 be made sufficient to assure that the rear end of the train has passed the highway H.

Although we have herein shown and 40 described only one form of apparatus embodying our invention, it is understood that various changes and modifications may be made therein within the scope of the appended claims without departing from the spirit and scope of our invention.

45 Having thus described our invention, what we claim is:

1. In combination, a railway track intersected by a highway, two normally closed relays E and F, means controlled by a train 50 moving along said track for opening relay E as it approaches said highway and for opening relay F as it crosses the highway, a signal relay K, a stick relay L, a thermostat having a winding and a normally open contact, a stick circuit for relay K including 55 a front contact thereof and a front contact of relay E, a pick-up circuit for relay L including a back contact of relay F and a back contact of relay K, a stick circuit for relay L including a front contact thereof and a back contact of relay K, a circuit for said thermostat winding including a front contact of relay F and a front contact of relay L as well 60 as a back contact of relay K, a pick-up circuit 65 for relay K including a front contact of re-

lay F and a front contact of relay L as well as said thermostat contact, and a highway crossing signal controlled by relay K.

2. In combination, a railway track intersected by a highway, two normally closed relays E and F, means controlled by a train moving along said track for opening relay E as it approaches said highway and for opening relay F as it crosses the highway, a normally closed relay K, a normally open stick relay L, a slow-acting device M, means responsive to the opening of relay E for opening relay K, means responsive to the opening of relay F while relay K is open to close relay L, means for subsequently holding relay L closed while relay K remains open, means for energizing said slow-acting device when relay F again closes provided relay L is closed and relay K is open, means for closing relay K after said slow-acting device has operated, 85 and a highway crossing signal controlled by relay K.

3. In combination, a railway track intersected by a highway, two normally closed relays E and F, means controlled by a train moving along said track for opening relay E as it approaches said highway and for opening relay F as it crosses the highway, a signal relay K, a stick relay L, a slow-acting device having a normally open contact and an energizing winding, a stick circuit for relay K including a front contact of relay E, a pick-up circuit for relay L including a back contact of relay F and a back contact of relay K, a stick circuit for relay L including a back contact of relay K, a circuit for the winding of said slow-acting device including a front contact of relay F and a back contact of relay L as well as a back contact of relay K, a pick-up circuit for relay K including a front contact of relay F and a front contact of relay L as well as the contact of said slow-acting device, and a highway crossing signal controlled by relay K.

4. In combination, a railway track intersected by a highway, two transformers G^E and G^F located in the trackway in such positions that a train influences transformer G^E as it approaches the highway, a transformer G^F as it crosses the highway, a source of current constantly connected with the primary of each transformer and the influence of a passing train being to materially reduce the output voltage of the secondary, a relay E connected with the secondary of transformer G^E, a relay F connected with the secondary of transformer G^F, a highway crossing signal, means responsive to the opening of relay E for setting said signal into operation, and means for stopping the operation of said signal after the expiration of a fixed interval of time following the opening and subsequent closing of relay F.

5. In combination, a railway track intersected by a highway, two transformers G^E 130

and G^F located in the trackway in such positions that a train influences transformer G^E as it approaches the highway, a transformer G^F as it crosses the highway, a source of current constantly connected with the primary of each transformer and the influence of a passing train being to materially reduce the output voltage of the secondary, a relay E connected with the secondary of transformer G^E , a relay F connected with the secondary of transformer G^F , a highway crossing signal, means responsive to the opening of relay E for setting said signal into operation, a slow-acting device set into operation by the opening of relay F, and means for stopping the operation of said signal after the operation of said slow-acting device has been completed.

15 In testimony whereof we affix our signatures.
